TISSUE DISPENSING DEVICE

David O. Walker, Johnston, S. C.

Application April 7, 1941, Serial No. 387,337

1 Claim. (Cl. 248—1)

This invention relates to a device for dispensing facial tissues or sheets of tissue used for various toilet purposes, and the primary object of the invention is to provide means whereby a dispensing carton containing facial tissues may be readily mounted within an automobile in a position to have the tissues conveniently withdrawn from the carton when desired by occupants of the automobile.

In carrying out the present invention, I provide the ordinary dispensing carton, which contains the sheets of tissue, with means whereby said carton may be conveniently mounted upon the glove compartment or sun visor commonly found in automobiles. The mounting means insures retention of the dispensing carton firmly in place and in an inverted position beneath the glove compartment or sun visor, although removal of the carton when empty may be readily effected so that a new filled carton may be substituted therefor.

The present invention consists in the novel form, combination and arrangement of parts hereinafter more fully described, shown in the accompanying drawings and claimed.

In the drawings:

Figure 1 is a perspective view of a tissue dispenser constructed in accordance with the present invention and substantially prepared for use with one of the protecting strips for one of the adhesive pads removed and the protecting strip of the other adhesive pad partially removed.

Figure 2 is a fragmentary perspective view looking toward the front of an automobile glove compartment with the dispenser of Figure 1 mounted in position upon said glove compartment.

Figure 3 is a vertical section on line 3—3 of Figure 2.

Figure 4 is an elevational view showing the tissue dispenser applied to a sun visor of an automobile.

Figure 5 is a bottom plan view of the construction shown in Figure 4.

Figure 6 is a top plan view thereof.

Figure 7 is an end elevation looking toward the left of Figure 5.

Figure 8 is a view similar to Figure 5 showing a modified form of the invention adapted for use in connection with a sun visor.

Figure 9 is a fragmentary transverse section showing a preferred manner of forming the dispensing slot for the carton forming part of the dispenser shown in Figure 1; and

Figure 10 is a view similar to Figure 9 showing

a modified form of construction for providing the dispensing slot of the carton.

Referring in detail to the drawings, facial tissues or sheets of tissue adapted for various toilet uses are ordinarily packed in a cardboard carton 5 whose top wall is scored so that it may be readily opened to provide a central longitudinal slot 6 through which the tissues may be drawn, one at a time, for use. Ordinarily, tissues are packed in the carton so that when one tissue is withdrawn, an edge of the succeeding tissue protrudes as at 7 to be conveniently grasped in withdrawing the same. The scoring of the top wall of carton 5 may be such that opposed portions 8 of the top wall may be folded inwardly as in Figure 9 or outwardly as at 8a in Figure 10 to provide the slot 6 and to reinforce the top wall of the carton at opposite sides of such slot.

The present invention aims to provide means for effectively mounting the carton in an inverted position against the under side of and upon a glove compartment 9 or a sun visor 10 such as commonly found in automobiles. This means preferably consists of an endless elastic band 11 threaded through slots 12 in the end walls of carton 5 near the normal bottom wall of said carton and extending through the carton in contact with such normal bottom wall, the portion of the band 11 outside the carton being of such size as to readily encircle the glove compartment 9 or sun visor 10 so as to pass around the ends and top of the same and thereby snugly position the carton 5 in an inverted position against the under side of said glove compartment or said sun visor as shown respectively in Figures 3 and 4. When thus mounted, the dispensing carton is disposed in a convenient position to have the tissues withdrawn therefrom by the occupants of the automobile when required for use.

In order to effectively assist the band 11 in holding the carton in place against the bottom of the glove compartment or sun visor and against forward or rearward displacement with respect to said glove compartment or sun visor, the normal bottom of the carton which is disposed uppermost when mounted in accordance with the present invention, is provided with a pair of longitudinally disposed slightly sticky adhesive pads 13 normally covered and protected by removable covering or protecting strips, one of which is shown partially removed in Figure 1 at 14. These protecting strips are applied by the manufacturer and remain in place when the carton is sold and until it is ready for use or mounting in the automobile.

It will be understood that the glove compartment 9 simply consists of a suitable hollow body or receptacle mounted at the rear of the instrument panel 15 and closed at the front by the usual door 16. The sun visor 10 is simply a well known rectangular opaque member of sheet like form suitably mounted as at 17 above the windshield 18 so that it may be swung into or out of operative position. It so happens that the elastic band 11 may be made of such a length that when slightly stretched it will snugly pass around the glove compartment 9 or the sun visor 10 so as to extend around the ends and across the top of said glove compartment or said sun visor and will dispose the dispensing carton in an inverted position snugly against the under side of said glove compartment or said sun visor.

When applied to the glove compartment 9, the carton will be disposed so that the adhesive pads 13 will engage the bottom of the glove compartment and effectively assist the band 11 in preventing shifting of the carton rearwardly or forwardly.

When it is desired to apply the dispenser to the sun visor 10, it is preferable to apply a band 25 to the sun visor so that the adhesive pads 13 will contact this band instead of directly contacting the sun visor itself. Such band may consist of a length of suitable fabric or other material 18 adapted to extend across the under side of the sun visor, then upwardly around the longitudinal edges thereof and across the top of the same, one end of the band having an adhesive tab 19 adapted to be adhered to the other end of the band when over-lapped onto the latter. In this way, the band is snugly applied transversely of the sun visor so as to encircle the latter snugly intermediate the ends of the same in position to have the adhesive pads 13 of the carton 5 contact the under side thereof. In mounting the present tissue dispenser either upon the glove compartment or upon the sun visor, it will be disposed in a convenient position for having the tissues withdrawn from the car-

ton when required for use by the occupants of the automobile. The manufacturer may provide the cartons 5 in attractive colors and devoid of excessive advertising so that the dispenser 5 will not have an objectionable appearance when mounted in the automobile.

While the embodiment of Figure 1 is adapted for use upon a glove compartment or sun visor, a form of the invention may be particularly 10 adapted for use upon a sun visor alone. In such case, the carton 5a disposed against the under side of the sun visor 10a, as in Figure 8, may be provided with two small transversely disposed mounting bands 11a, instead of the single longitudinally disposed band 11. When the two bands 11a are used as in Figure 8, they will pass through slots in the front and rear walls of the carton instead of in the end walls of the same and will pass through the carton in contact with 20 the normal bottom wall thereof as is the case with the band 11 in Figure 1. The use of two bands 11a adapted to pass around the visor adjacent the opposite ends of the latter will render unnecessary the use of the adhesive pads 13 or a protecting band 19 for the sun visor.

From the foregoing description, it is believed that the construction and manner of use, as well as the advantages of the present invention, will be readily apparent to those skilled in the art.

What I claim as new is:

In combination with a support including a substantially rigid panel and a tissue dispensing container having slots in opposite walls thereof, an endless elastic band extending through the slots and about the panel longitudinally thereof to urge the container always in the direction of one face of the panel, a second band extending tightly about the panel and transversely thereof, and adhesive pads applied to the container and adhering to the second band under the influence of the elastic band to prevent the latter and the container from accidentally shifting relative to the panel.

DAVID O. WALKER.
